MECHANICAL ACTIVATION

Milton C. Shaw, Hampton, Va., assignor to The Cincinnati Milling Machine Co., Cincinnati, Ohio, a corporation of Ohio

Application April 3, 1942, Serial No. 437,607

15 Claims. (Cl. 260—658)

1
This invention relates to method and apparatus for initiating and/or carrying out chemical reactions.

One of the objects of the invention is to provide an improved process for initiating chemical reactions and for carrying out chemical reactions and for controlling the reaction rate of chemical reactions.

Another object is to provide a method of initiating autocatalytic reactions.

Another object is to provide a method of obtaining high local temperatures and pressures, and freshly formed surfaces, for initiating and/or carrying out chemical reactions.

Another object is to provide a method and apparatus for utilizing high temperature and/or pressure for initiating chemical reactions without using container apparatus especially designed to withstand such high pressures and/or temperatures.

Another object is to provide an improved method of carrying out chemical reactions at a reduced cost.

Another object is to provide new and useful chemicals and mixtures of chemicals.

Another object is to provide new and useful apparatus adapted among other things to carry out the method of the present invention.

Other objects will be in part obvious and in part pointed out hereinafter.

The invention accordingly consists in the steps and combination of steps and the features of construction, combinations of elements, and arrangements of parts as will be exemplified in the method and the structure to be hereinafter described and the scope of the application of which will be indicated in the following claims.

In the accompanying drawings,

Figure 1 is a front perspective elevation of an apparatus adapted to carry out the method of the invention;

Figure 2 is a cross-sectional view of the apparatus of Figure 1 taken on line 2—2 of Figure 1;

Figure 3 is a cross sectional view taken on the line 3—3 of Figure 2;

Figure 4 is a detailed view of a cutting element of Figure 1;

Figure 5 is a diagrammatic drawing showing a cutting element such as might be used in the apparatus of Figure 1 in the process of forming a chip; and

Figure 6 is a diagrammatic drawing of the apparatus of Figure 1 set up for continuous operation.

2
Corresponding reference characters refer to corresponding parts throughout the drawings.

It is well known that the rate of reaction between chemicals is favorably influenced by elevated temperatures, and usually by elevated pressures. Also in the case of endothermic reactions wherein heat is absorbed the tendency to react is increased by increased temperature. Likewise in the case of reactions wherein the 10 total volume of the reaction system decreases as the reaction proceeds the tendency to react is increased by elevated pressure. Also, when the reaction is between a solid and a fluid the reaction is favored by the cleanliness of the 15 surface of the solid, i. e., by an approach toward a nascent condition and freedom from any foreign film. Such is also frequently true of so-called catalytic reactions wherein one reactant serves to initiate chemical reactions between 20 other reactants.

I have discovered a method and apparatus that is highly useful in initiating and carrying out chemical reactions and that apparently utilizes high temperatures and/or pressures 25 and/or nascent surfaces in causing such reactions to occur. The connotation to be given to the word "nascent" in this specification and in the claims is that which appears in Webster's International unabridged dictionary which defines 30 nascent as "coming into existence." Thus, a nascent surface is a surface being made or coming into existence.

Further, I have discovered a method and apparatus for obtaining unusually high temperatures and pressures, and for simultaneously creating fresh nascent surfaces, and for utilizing such temperatures, pressures and surfaces for initiating chemical reactions. Thus I have discovered that the high localized temperatures and 40 pressures that prevail, and the nascent surfaces that are created during the mechanical "working" of a solid so as to continually expose fresh surfaces thereof, as for example by removing chips therefrom, may be utilized in the presence of a reactant fluid or fluids and/or reactant solid or solids to favor chemical reactions between such solid or solids being cut and fluid reactant or reactants present or between fluid reactants alone or between reactant solids alone. I have 50 discovered further that chemical reactions which are otherwise difficult to start, or which cannot be started by conventional means, or which cannot be conveniently controlled after starting, may be conveniently started and carried out by 55 this process of thus "working" a solid. This

process for convenience will herein be referred to as "mechanical activation."

By using this "mechanical activation," i. e., the mechanical working of a solid continually to expose fresh surfaces thereof and create high localized temperature and pressure conditions in the presence of fluid and/or solid reactant or reactants, chemical reactions may be positively forced to take place. The degree of the high local temperature is limited only by the melting temperature of the solid being worked on. Likewise the high local pressures are limited only by the hardness of the solid being worked on.

Although the amount of the reactants thus caused to react may be small in comparison with the total bulk to be reacted, in the instance where the reactant product or other catalyst is necessary to carry on the reaction at a favorable rate, this small amount of product formed by the working of the solid may be sufficient to produce the desired rate of reaction. Thus in instances where the reaction is autocatalytic, the reaction caused to take place during the working of the solid may continue at normal temperature as the result of an autocatalytic effect. However, in other instances it may be desirable to utilize higher temperatures and pressures to increase the reaction rate of the reaction started by the "mechanical activation" action.

Thus I have discovered that in the particular case of an autocatalytic reaction, the product of the "mechanical activation" (i. e., reactant solid surfaces on which a reactant fluid was caused to react) may be stored, and at a subsequent time caused to continue to react with the fluid reactant under temperature and pressure conditions such as to give a favorable reaction rate.

Also the temperature and pressure conditions of the bulk of a reactant or reactants before and/or after the "mechanical activation" operation may be controlled at such value as to maintain a favorable reaction rate, simultaneously with and subsequent to the "mechanical activation" operation. In this manner the reaction positively started by the "mechanical activation" on the surface of the solid reactant may be caused to continue to react at a favorable rate.

In the case of autocatalytic reactions these temperature and pressure conditions favorable to the desired reaction rate may be well below the temperature and/or pressure condition necessary to initiate the reaction. Under such circumstances where the temperature and/or pressure condition necessary to start the reaction is provided by the conventional means, the temperature and pressure cannot be lowered with sufficient rapidity and as a result the reaction once started may well proceed with destructive violence. With the present invention, however, the high temperatures and pressures utilized are localized and may be obtained while the bulk of the reactants are at a much lower temperature and pressure and such as to continue the reaction at a desired reaction rate.

Thus I have discovered a method of carrying out chemical reactions, without the necessity of providing container apparatus for withstanding the high temperature and pressure conditions, previously considered as necessary for initiating such reactions, and for carrying on such chemical reactions at favorable reaction rates conveniently controlled by the regulation of temperature, pressure, concentration, and mechanical activation rate conditions as will be described. In other words, by controlling the rate at which the me-

chanical activation operation is carried out, and by controlling the temperature and pressure conditions of the reactant products the entire reaction may be controlled and run under uniform conditions.

Thus chemical reactions may be initiated, controlled and carried out without explosive violence and at low bulk temperatures, which chemical reactions would otherwise have to be initiated at elevated temperatures using very limited quantities of reactants because of the violence of the reaction, or employing flash heating and cooling to initiate and control the reactions. With this mechanical activation process exothermic reactions may also be conveniently carried out without unusual provision for the dissipation of heat from the reactants and reactant products. This may be accomplished because the mechanical activation operation may be carried out at such a controlled rate that the bulk reaction will not take place faster than the heat may be dissipated by usual means.

Also because the mechanical activation may be so positive in causing reactions to take place, it is not always necessary to exclude substances whose presence is otherwise unfavorable to the reaction.

As will appear from the embodiment and examples hereinafter described, the mechanical activation apparently has utility wherever the high temperatures, and/or the high pressures and/or the nascent surfaces created by the mechanical working of the solid are favorable to chemical reactions. Thus mechanical activation may be used to carry out many chemical reactions which are today not practical or even possible because they are too difficult to initiate, or if initiated at high temperatures, proceed so violently as to be uncontrollable.

Before describing further the details of the embodiments chosen to illustrate the method of the invention and the examples chosen to illustrate the embodiments, one mechanical activation apparatus by which an embodiment of the method invention may be practised will be described and its operation briefly analyzed. In the embodiment chosen to illustrate the method of the invention, the length of a solid rod is continually shortened (in the presence of fluid reactants) by removing chips therefrom by means of a cutting element or cutter. It is, of course, understood that other methods may be used continuously and mechanically to present fresh surfaces of a solid, while simultaneously creating high local surface temperatures and pressures.

Referring to Figures 1 and 2, a cutting apparatus is shown, generally indicated at 1, driven by a motor and speed varying transmission, generally indicated at 2. The drive between the cutting apparatus and the transmission is a V-belt 3 which drives a sheave 4 mounted on a shaft 5 running in bearings 6 mounted in a suitable base 7. The shaft 5 carries at its right end a cutting element or cutter 8, adjustably mounted in a conventional manner in a slot 9 of the shaft.

As best seen in Figure 4 the cutter illustrated has a rake angle of 15° (i. e., the angle that the leading face 8a of the cutter makes with a plane normal to the path of motion of its cutting edge 8b) and a clearance angle of 3° (the angle that the flank 8c of the cutter makes with respect to the path of motion of the cutting edge 8b). Other angles may be used to suit the needs of the operation.

As shown in Figures 1 and 2, the cutter rotates

in a cylindrical reaction chamber 10 provided in a housing 11. The cutter shaft extends forwardly through a hole 12 in the rear wall of the chamber 10. Suitable pressure tight bushings 13 are provided to prevent fluid from escaping from the chamber 10 along said shaft. The front wall of the chamber 10 has a window, i. e., a glass plate 14, suitable mounted on the front wall of the housing 11 by clamping rings 15 in such manner as to make the window fluid tight.

The solid to be cut by the cutter in carrying out the mechanical activation operation, is fed in the form of a rod 16 to the cutter 8. The rod (Figure 2) is fed down through bushings 17 which support the rod close to the cutter. Suitable packings 18 are provided to prevent escape of fluid from the chamber past the rod.

To feed the rod 16 down through the bushing 17 a feeding mechanism is provided, adapted to feed the rod 16 to the cutter at any desired rate. To this end and referring to Figure 1 the rod is held by an arm 19 extending forwardly from a slide 20, mounted for vertical sliding in dovetail grooves 21 provided in a vertical support 22 extending upwardly from the supporting base 7.

The slide 20 is fed downwardly at a controlled rate by a rotatable screw 23 which passes through suitable female screw threads provided in the slide 20. The upper end of the screw 23 is supported in a suitable frame and carries a worm gear 24 adapted to mesh with a worm 25 driven by a sheave 26, as diagrammatically shown in Figure 1. Sheave 26 is driven through a V-belt 26a by means of a motor and transmission 26b of the same type as is used to drive the shaft 5. With this construction the threaded screw 23 may be rotated to feed the rod 16 to the cutter at any desired rate.

Still referring to Figure 1 the chamber 10 is shown as provided with a number of inlets and outlets. To flow gaseous fluids into the chamber to maintain the desired atmosphere therein, a pipe 27 is provided to which the source of fluid may be connected. The pipe 27 is connected with a passage 28 provided in the housing 11 and entering the chamber 10. A needle valve 29 is provided in the passage 28 to regulate the flow of fluid into the chamber. Flow of gas out of the chamber is provided for by an outlet passage 30 in housing 11 connected with an outlet pipe 31. A needle valve 32 is provided so that by regulating the two valves 29 and 32 the desired pressure may be caused to exist in the chamber 10. Of course, these valves could be automatic pressure regulators or other kinds of controllers.

A liquid inlet is provided to the chamber 10 through the medium of a pipe 33, a valve 34 and a passage 35 in the housing 11. Referring to Figure 2, an outlet through which the reactant products may be drawn off from chamber 10 is provided in the form of a passage 36, in which is provided a suitable valve 37.

It is understood that with these various controlled inlets and outlets, liquid level in the chamber 10 may be suitably adjusted, if liquid is used; and also that the fluid pressures in the chamber 10 may be suitably adjusted if pressures other than atmospheric pressure are needed. Also while the mechanical activation process is being carried out, gas may be caused to flow continuously through the chamber 10. Likewise, reactant liquids may be caused to flow continuously through the chamber 10 as will be described.

In other words, it is intended that the apparatus here shown may be connected up in any con-

venient manner to maintain in and/or flowing through the chamber 10 the amount of liquid, and fluid pressure desired.

Referring to Figures 1 and 3 means are provided to heat or cool the housing 11 and so the contents of the reaction chamber 10. This means comprises a passageway 38 provided in the housing 11 and extending around the chamber 10. The inlet is shown as a pipe 39 having a valve 40 and the outlet is shown as a pipe 41 having a valve 42. A plug 43 is provided in the passageway 38 to separate the inlet and outlet pipes 39 and 41 and so prevent short circuiting of the circulated fluid. By varying the temperature and quantity of the medium circulated through the passageway 38 the temperature in the chamber 10 may be regulated. The temperature maintained may be read by means of a thermometer 44.

The motor and the transmission 2 may be of any desired type, but where different chemical reactions are to be carried out in the apparatus, the drive system should be capable of a wide speed variation to drive the cutter 8 at various speeds because of the effect that the speed of the cutting operation may have on chemical reactions. A transmission such as shown in the Heynau Patent No. 1,950,675 may be satisfactory.

Referring to Figure 4 an enlarged view of the cutter 8 and the rod 16 is shown in the process of cutting a chip 45 from the end of the rod. The cutter is seen to have a leading or cutting edge 8b and a leading face 8a over which the chip passes as the cutting edge 8b forms the chip and advances across the rod 16. Liquid fluid reactant, in the present embodiment, is supplied to the cutting operation by the cutter 8 which is intended to pass through the liquid in the chamber 10 each time the cutter rotates. Other convenient ways of supplying the reactant fluid to the cutter may of course be used.

Referring now to the mechanics of the cutting operation itself there is shown in Figure 5 a diagrammatic and magnified picture of a chip riding over the cutter face. This drawing shows that as the cutting edge 8b of the cutter 8 advances across the solid (for example, the rod 16) the chip 45 that is formed rides over a portion of the leading face 8a of the cutter 8. Although the chip 45 is shown flat against the face 8a of the cutter, actually the contact between the chip and cutter is probably only at a large number of small areas.

Localized pressures (force per unit area) of a high order are developed at these points of contact between the sliding surface of the chip and the cutter face 8a. These pressures increase with increased hardness of the solid being cut. If the solid being cut is metal then the pressure is increased further because of the "work hardening" of the metal during the cutting operation.

These localized pressures that may be obtained between the chip surface and the leading face of the cutter are limited only by local surface hardness of the material being cut, i. e., only by the hardness of the metal at the points of contact between the chip and the cutter.

By increasing the thickness of the chip being cut, as for example, by increasing the feeding speed of the rod 16 while keeping the same cutting speed of the cutter 8, although the force required to remove the chip is greater, the actual pressure in pounds per square inch between the chip surface and the cutter is not increased but

instead the chip is caused to contact the cutter face 8a over a greater surface area.

High localized temperatures are created at these points of contact by the chip sliding along the cutter face. These localized temperatures may become very high and in fact when metal is being cut may reach temperatures which actually are in the neighborhood of the melting point of the metal. These localized temperatures are a function of the speed of the cutter among other factors, and in general increase with increasing speed. Thus the localized surface temperatures may be varied and controlled over a wide range by controlling the speed of the cutter. But although these localized high temperatures exist only at the points of contact, actually the average temperatures of the juxtaposed chip surface and cutter face 8a may be elevated way above the temperatures of the body of the rod 16 or cutter 8. And even these average temperatures may be far in excess of those temperatures readily obtainable in autoclaves. As the cutter advances across the rod 16 to form the chip, new surfaces (chip and rod) are created, which surfaces at the moment of their creation are nascent and are free from foreign material. Thus, in the case where the rod 16 is one of reactants the chip surface in this nascent condition is in a highly reactive state.

The point contacts between the chip surface and the cutter face 8a probably form what might be described as a number of small bridges which produce a labyrinth of capillaries or interstices which are powerfully active to draw the reactant fluids into the zone of action between the chip and cutter surfaces.

Since it is believed desirable to have the fluid reactants enter these interstices at the chip-cutter interface, precautions are taken to make the conditions for the entry of the reactant fluids into the interstices as favorable as possible. To this end not only is the cutter supplied with and wetted by the reactant fluids but also fluid pressures surrounding the cutter 8 may be employed to assist in the entry of the reactant fluids into the interstices between the moving chip-cutter interface.

So also other factors may be employed in making this fluid entry into the interstices as favorable as possible. Thus the viscosity of the reactant fluids and the surface tension or interfacial tension between the reactant fluids, the chip surface and the cutter face 8a may be conveniently modified to increase the tendency of the reactant to enter the interstices.

In connection with the matter of selecting the proper speed for the cutter edge I have pointed out that as the speed of the cutter is increased the temperature at the chip-cutter interface also increases, and in general increasing the temperature is favorable to chemical reactions. But increasing the speed of the cutter gives less time of contact between the chip surface and the leading cutting face of the cutter and consequently (1) gives less time for the reactant fluids to enter the newly forming interstices at the chip-cutter interface, (2) gives less time for the chemical reaction to proceed on a given area of chip surface at the chip-cutter interface, and (3) decreases the flow to the chip-cutter interface because of the increased effect of the chip in causing the reactant fluid to run counter current to the desired direction of flow. Consequently in practising the mechanical activation process it is desirable to select the cutting speed at which

the balance of the abovementioned factors gives the most favorable reaction.

In this connection also the matter of the viscosity and surface tension of the reactant fluids is to be considered for, in general, the greater the viscosity of the reactant fluid the more difficult it is for it to enter the interstices at the chip-cutter interface and so the more time must be allowed for such entries. Also, where the surface tension between the reactant fluid and the solid being cut and between the fluid and the cutter face is unfavorable, higher cutter speed may have to be sacrificed to permit the entrance of the reactants into the interstices. However, as above pointed out, by raising the pressure of the fluid surrounding the cutter, the fluid reactants may be aided in entering the interstices as the cutting speed is increased.

Thus, as above described, with this apparatus reactant fluids may be subjected to high pressures and temperatures on nascent surfaces, and reactant fluids and solids may be brought together under the most favorable conditions for carrying out reactions between them, where temperature and/or pressure and/or cleanliness of surface are important factors.

Although I have disclosed a theory of the mechanics by which I believe the results are accomplished in practising the mechanical activation process, I do not intend my patent to be limited by this theory, for whatever the explanation may be, the fact remains that I have discovered that the use of the mechanical activation process creates conditions that are unusually favorable to chemical reactions between the reactants involved.

The general behavior of the method and of the apparatus for carrying out the method in a batch process may be demonstrated by the synthesis of hexachlorethane from carbon tetrachloride by causing carbon tetrachloride and aluminum to react. To this end an aluminum rod may be inserted in the bushing 17 and clamped in the arm 19 of the feeding mechanism as described. Since this particular reaction once started by the cutting action continues at a satisfactory reaction rate if the temperature is kept at or near the boiling point of carbon tetrachloride, the chamber 10 is heated to that temperature by regulating the flow of a suitable heating medium through the passageway 38 of the housing 11.

To avoid side reaction produced by moisture and oxygen, a source of dry nitrogen is connected to pipe 27 and valve 29 is set to pass the desired amount of nitrogen through the chamber 10. To prevent loss of carbon tetrachloride by evaporation, a suitable condensing apparatus may be attached to passageway 31, to return to the system carbon tetrachloride evaporated during the operation. The valve 32 shown in the line is opened, because the process is carried out at atmospheric pressure.

Now carbon tetrachloride is introduced into the chamber through the pipe 33 and the latter is closed by valve 34. The liquid level of the carbon tetrachloride is maintained such as at least to touch the cutter 8 so that as the cutter rotates it is supplied with carbon tetrachloride.

The motor 2 is now turned on with the transmission adjusted to give the cutter a speed of 300 ft./min. which speed is favorable to this reaction. Also the feed mechanism is started to feed the aluminum rod at a rate sufficient to produce chips of the desired thickness. Almost

instantly with the starting of the motors, the chips formed are seen to be reacting with tetrachloride and the reaction yields hexachlorethane, aluminum chloride and a red substance which has not been identified beyond the fact that it is an aluminum chloride complex.

By making the cuttings or chips sufficiently thin and by keeping the temperature of the bulk carbon tetrachloride sufficiently high the chips may be caused to be used up in the reaction as rapidly as they are formed. After the desired amount of aluminum has been cut, the reaction products, i. e., the red substance and aluminum chloride and hexachlorethane in solution in carbon tetrachloride, may be withdrawn through the valve 31 and passage 38.

Or the operation may be carried out with the chip size (i. e., thickness) and the temperature condition so regulated that the aluminum chips are not wholly used up or dissolved as they are cut, and with this type of operation after sufficient aluminum has been cut, the cutting is stopped and the aluminum and remaining carbon tetrachloride may be left to complete the reaction in the reaction chamber 10 or may be withdrawn through the valve 31 to a separate container where the reaction may be completed under favorable temperature conditions.

Indeed the factors governing the reaction rate of the reaction initiated by the cutting may be so adjusted by regulating the temperature condition of the bulk of the carbon tetrachloride that relatively little reaction takes place between the aluminum cuttings and chips in the bulk of the carbon tetrachloride in the chamber 10. Under these circumstances the carbon tetrachloride and chips may be withdrawn from the reaction chamber and even preserved if maintained at sufficiently low temperature for some time without further reaction taking place between the aluminum and the carbon tetrachloride. But when the temperature condition of the carbon tetrachloride is later raised to one favorable to a rapid reaction rate between the aluminum and the carbon tetrachloride, the reaction may be caused to proceed rapidly to completion as in the first example given. Thus, the aluminum chips cut in carbon tetrachloride may be preserved and later used as a means for synthesizing hexachlorethane from carbon tetrachloride.

In other words, the act of presenting a fresh nascent surface of the aluminum, while simultaneously creating local high pressure and temperature conditions in the presence of carbon tetrachloride leaves on the chip surface reactant products which are adapted to catalyze the reaction between the aluminum and carbon tetrachloride at a favorable reaction rate under favorable temperature and pressure conditions.

That the mechanical activation operation caused a chemical reaction to take place between the aluminum chips and the carbon tetrachloride is further shown by the fact that aluminum chips cut in the same manner and in the presence of an inert atmosphere, but not in the presence of carbon tetrachloride, when subsequently put in carbon tetrachloride and under temperature conditions favorable, in the preceding example, to rapid reaction between the aluminum and carbon tetrachloride do not visibly react for some considerable time. In other words, the red substance does not form for a considerable time, but after it does form then the reaction continues somewhat in the same manner it did in the re-

action chamber 10. This delay in the starting of the reaction (which delay may be variable and of uncertain duration) is commonly referred to as the induction period of the reaction.

In the foregoing description we have seen how the temperature condition within the chamber 10 may be utilized to control the reaction rate of the reaction started by the cutting operation. Likewise, the pressure condition may be utilized in several ways to favor a more rapid reaction rate or a slower reaction rate. Thus if the temperature most favorable to a desired reaction rate is above the boiling point of the liquid reactant, the valve 32 in the outlet line 31 may be placed beyond a condenser connected to the outlet and may be adjusted to maintain a back pressure in the chamber 10 sufficient to raise the boiling point of the liquid reactant to that corresponding to the temperature desired.

Also, where a higher pressure is desired to obtain a greater concentration of the fluid reactant, if such reactant is a gas, for example, or if a high pressure of the fluid actually is necessary to the desired reaction rate, the inlet valve 29 and the outlet valve 32 may be operated to maintain the desired flow to maintain the desired back pressure.

As above described, the higher pressure in chamber 10 may also be used to assist the reactant fluid to enter the interstices at the chip-cutter interface which is constantly moving as the cutter forms the chip.

We have also seen from the foregoing description that a special atmosphere may be desirable for continuing the reaction in the chamber 10. Thus in the aluminum-carbon tetrachloride reaction, since moisture and oxygen causes side reactions, a dry nitrogen atmosphere was conveniently maintained in the reaction chamber.

In addition to temperature, pressure and concentration conditions, other conditions or effects of known nature may be used to favor the rate of the reaction started in the chamber 10 by the mechanical catalysis. Thus, for example, electrical potentials, vibrations, magnetic influences, etc., may be combined with the mechanical activation to facilitate desired reactions.

A study of the red substance produced by the reaction between aluminum and carbon tetrachloride shows that it itself is a highly reactive substance. When present with the aluminum chips and carbon tetrachloride it apparently catalyzes their reaction. The red substance can be stored in carbon tetrachloride providing it is protected from moisture and maintained at a sufficiently low temperature. The activity of this red substance is shown by its active reaction when brought into contact with such chemicals as benzene, toluene, ethyl acetate, petroleum ether, ethyl alcohol, ethyl ether, acetone, pyridine, dioxane and water by which it is hydrolyzed.

Having described generally how the method of the invention may be carried out in the apparatus shown, and having given a specific example, I will now discuss further the effects of various factors bearing on the mechanical activation method and will give examples to show various uses that may be made of the invention.

Solid reactants which may be used are those which may be given sufficient surface hardness to create elevated localized pressures during the cutting action or other mechanical action continually to present fresh surface. Such solids may be reacted with other reactants where the elevated pressure is a controlling factor in start-

ing the reaction. Solid reactants may be used which have sufficiently high melting points to give high temperature during the cutting action where elevated temperatures are an important factor in starting the reaction. Where both pressure and temperature are of importance solid reactants may be used with which both elevated temperatures and pressure can result from the cutting action.

When a solid having such characteristics is capable of reacting with a fluid (gaseous or liquid) the reaction may be initiated in the apparatus shown in Figure 1 even though the reaction would not take place satisfactorily or only with difficulty, by the usual temperature and pressure obtaining methods wherein heat is supplied from external sources and the reactions are carried out in closed high pressure chambers.

As another example of a reaction that is conveniently initiated by the mechanical activation process, aluminum chips may be cut in chamber 10 of the apparatus of Figure 1 in the presence of chloroform, and under normal temperature, and pressure conditions but in the absence of appreciable oxygen and moisture. The aluminum is caused to react with the chloroform to form a red substance (which is an aluminum chloride complex) and carbon, and other products. Although the reaction carried out under these conditions may not show itself visually instantly, after a lapse of a short period of time measured in minutes the chloroform assumes a red color and eventually a black color. By refluxing the reaction products, the reaction rate may be considerably increased. The cutting speed evidently has an important bearing on the mechanical activation in this reaction for, as we shall point out later, as the cutting speed changes the reaction rate changes.

That a reaction is actually caused to take place between the aluminum and chloroform by the mechanical activation operation is shown by the fact that when aluminum chips are cut in the presence of an inert atmosphere, free from moisture and oxygen, and free from chloroform, and are subsequently refluxed in chloroform, it takes a very considerable period of time for the reaction between the aluminum and the chloroform to start.

Still another type of reaction that may be advantageously carried out by the mechanical activation process is the so-called Grignard type of reaction. This type of reaction is well known and is used to synthesize more complex organic compounds from simpler compounds. In carrying out this type of reaction, a Grignard reagent comprising an organo-magnesium compound of the type R—Mg—X, is first made. Other metals may be substituted for the magnesium to give a "Grignard" type of reagent. This reagent is generally made by starting with an organic halide which is caused to react with the magnesium or other metal in a suitable solvent to yield the organo-magnesium halide.

This reagent is then either hydrolyzed to exchange the inorganic radical for hydrogen or is caused to react with an organic compound to yield a synthesized condensation product.

In carrying out the Grignard type of reaction heretofore it has been very important to keep the reaction between the organic halide and the magnesium (or other metal used) absolutely free from moisture, in order for the reaction to start and continue. Also the reaction is generally started only by resorting to elevated temperatures

and/or catalysts that may introduce impurities into the product. The elevated starting temperatures frequently produce difficultly controlled reaction rates once the reaction starts. Many devices and procedures have been designed to solve these problems thus encountered in carrying out the Grignard type of reaction.

With the present mechanical activation process the initial reaction between the organic halide and the metal can be readily initiated without attention to the absence of moisture or to the presence of high bulk temperatures. After the reaction is initiated it may be carried out in the usual manner except that in the presence of water the mechanical activation must be continued. In fact, at least one of the Grignard type of reactions may be carried out at room temperature and in the presence of moisture. Consequently there is a considerable saving in the cost of materials because of the elimination of requirement of anhydrous chemicals to carry out the synthesis.

As an example of the present mechanical activation process utilized to carry out a Grignard type of synthesis, a magnesium rod may be placed in the apparatus of Figure 1 as described. A solution of phenyl bromide in ether is added with no effort being made to exclude water or moisture. With the apparatus at room temperature, the motor and transmission 2 set to give a cutting speed of 125 feet per minute, and the feed adjusted to give the desired chip thickness, the cutting is started. The reaction between the chips and phenyl bromide starts to take place immediately and quietly. The phenyl magnesium bromide thus obtained may be hydrolyzed or reacted with other compounds to synthesize the final desired compound. Thus phenyl magnesium bromide may be caused to react with ethylene oxide and the resulting product when treated with water gives benzyl carbinol.

To start this Grignard reaction in the conventional manner not only must the reactants be free from moisture but the temperature of the reactants must be elevated as by refluxing in order to start the reaction. Frequently, however, the reaction started in this manner may proceed violently and uncontrolled, and so is a dangerous one to carry out. Thus the present example therefor shows how the mechanical activation process may be conveniently used to control and regulate the rate at which a chemical reaction is caused to proceed for with the mechanical activation process by choosing a suitable cutting speed this Grignard reaction is caused to take place quietly at room temperature or slightly above.

The above examples have involved the action of a liquid reactant with a solid reactant. As an example of the use of mechanical activation to cause a reaction between a vapor reactant and a solid, the aluminum-carbon tetrachloride reaction may be carried out with the carbon tetrachloride supplied in vapor form.

To this end the apparatus, Figure 1, is connected up in the following manner. Heating fluid is supplied to the passageway 38 and controlled to maintain the walls of the reaction chamber 10 above the boiling point of carbon tetrachloride at atmospheric pressure. The liquid inlet valve 34 and the outlet valve 31 are closed. Superheated carbon tetrachloride vapors are supplied to the pipe 27, the valve 29 being open. Excess carbon tetrachloride vapors pass from the chamber 10 through the valve 32 to a suitable condenser and the liquefied carbon tetra-

chloride is collected in a suitable container outside the chamber 10.

Under these conditions the motor 2 is started and the transmission is adjusted to give the cutter a speed of 300 ft./min. (and using the same feeding speed as before) and the aluminum chips that are cut and fall into the chamber and into the outlet above the valve 31 will be found to have on their surface products of reaction between the aluminum and the carbon tetrachloride. This is shown by the fact that a red substance is visible on the surface of the chips so cut, and that these aluminum chips when subsequently placed in carbon tetrachloride liquid immediately commence to react with the carbon tetrachloride as when the aluminum chips were cut in the presence of liquid carbon tetrachloride.

This example demonstrates the use of the mechanical activation process for preparing a highly reactive product which may be preserved and subsequently caused to react when desired. Thus, the aluminum chips cut in the presence of the vapor carbon tetrachloride may be stored in an inert atmosphere and when subsequently placed in carbon tetrachloride may be caused to react with it.

The mechanical activation process may also be used to initiate and/or carry out a reaction between two fluid reactants and a solid. As an example of this type of reaction a so-called Barbier reaction may be caused to take place. This reaction is a special kind of Grignard reaction and in which the organic halide, the metal (magnesium) and the hydrolizing agent or other compound are all caused to react in the same chamber at the same time. As an example of a Barbier reaction phenyl magnesium bromide and the hydrolizing agent water may be caused to react simultaneously to produce benzene and other products. This process may be carried out in the apparatus of Figure 1 as follows. A mixture of ether, phenyl bromide and water is placed in the reaction chamber 10, said mixture having the following approximate proportions:

Parts	45
Ether	25
Phenyl bromide	6
Water	1.4

With the inlet and outlet valves 34 and 31 closed and with the valves 29 and 32 opened to pass nitrogen through the reaction chamber the cutter 8 is given a cutting speed first of 125 ft./min., and after a short period of time this speed is increased to 300 ft./min. to cut a magnesium rod 16 in the manner above described. The reaction soon starts to take place to form benzene and other products.

This example of a Barbier reaction could not be carried out by any known methods because the presence of water acts to prevent the reaction taking place even though elevated temperatures and catalysts are used.

Referring to Figure 6 the apparatus in Figure 1 is diagrammatically shown set up to carry out in a continuous process the Grignard reaction above described for making phenyl magnesium bromide, the procedure for which has already been described. To carry out this reaction continuously the apparatus is set up as follows. A tank of nitrogen is shown at the right of the reacting apparatus 1 shown in the center of Figure 6. The tank of nitrogen is connected through a valve 46, and a drier 47 to the pipe 27 of the apparatus. The nitrogen escapes from the chamber 10 through the usual pipe 31 and valve

32. But inasmuch as the reaction is carried out at an elevated pressure because such pressure aids in reducing the rate of evaporation of the fluid reactants, the valve 32 is pinched to restrict the flow of nitrogen from the chamber. A pressure gage 48 is provided in the line 31 to indicate the pressure maintained in the chamber 10.

For the present reaction a pressure of 30 pounds per square inch (above atmospheric pressure) may be satisfactory. A solution of phenyl bromide and ether, in the usual proportions, is placed in the supply tank 49 located above the cutting apparatus. The supply tank is connected at its bottom with the chamber 10 by means of the intake pipe 33 and the valve 34 previously described.

Inasmuch as the pressure in the chamber 10 will be above atmospheric, static pressure is supplied to the liquid in the tank 49 in order to cause it to flow into the chamber 10. This is conveniently accomplished by running a pipe 50 having a valve 51 from the output end of the nitrogen drier to the top of the tank 49. A pressure gage 52 indicates the static pressure within the tank 49. This pressure may be built up to the desired value in the tank by cracking the valve 51 and allowing nitrogen to pass into the tank 49 until the desired pressure is built up, at which time the valve 51 is closed and the static pressure is locked in the tank.

Now by cracking the valve 34 the solution in the tank 49 may be caused to flow into the chamber 10 at the desired rate.

The liquid passes out of the chamber through the valve 37 and a pipe 53 to a tank 54 open to the atmosphere but filled with an inert gas and connected to the atmosphere through a suitable drier 55. Of course, after the liquid level in the reaction chamber is built up to the point where the cutter 8 passes through the liquid as the cutter rotates, the valve 37 has to be open just sufficient to permit as much liquid to flow out of the reaction chamber 10 as flows into the reaction chamber.

With the apparatus thus set up and the fluids supplied to and removed from the chamber 10 as described, and with the cutter 8 driven at a speed of 125 ft./min. the magnesium chips formed react continuously with the liquid in the chamber 10 and the rate of removing metal may be adjusted so that the magnesium chips are dissolved as fast as they are formed. The product that goes to the tank 54 is a solution of phenyl magnesium bromide in ether, with small amounts of other products. A screen may be provided to retain the chips in the chamber until they dissolve.

It has been pointed out that the speed of the cutter 8 may have an effect on the operation of the process. This is demonstrated by the fact that in cutting aluminum chips in the presence of carbon tetrachloride as the cutting speed increases from the very slow speed of 35 ft./min. the rate of the chemical reaction brought about decreases until a speed of approximately 45 ft./min. is reached. Thereafter as the cutting speed is increased the reaction rate increases rapidly and this increase extends over an appreciable range of speed increase.

The same also holds for the cutting of aluminum in chloroform, only the values of the speeds and proportions are different. The effect of the speed of the cutter on the reaction is also shown by the effect of the speed on the phenyl bromide magnesium reaction. Whereas

the magnesium and phenyl bromide react quietly at room temperature and at a cutting speed of 125 ft./min., if the cutting speed is increased to 300 ft./min. with the apparatus of Figure 1 the reaction takes place with violence and at an uncontrollable rate.

These examples are sufficient to show that in practising the process of mechanical activation the speed of the cutter may be an important factor in the successful operation of the process.

I claim:

1. In the art of manufacturing chemical compositions the steps of introducing a reactant solid metallic body into a chamber, continually cutting chips from the body within said chamber, supplying simultaneously liquid reactant to surfaces of said chips while said surfaces are being formed, to cause the liquid reactant and the solid reactant, subjected to conditions existing during and created by the cutting action such as the conditions of the high localized pressures and temperatures caused by the cutting action, to react readily at said surfaces, subjecting the chips thus formed to a body of the liquid reactant in said chamber to cause the reaction thus initiated to proceed, and collecting a product of the reaction.

2. The method of facilitating a Grignard type of chemical reaction comprising the steps of continually cutting chips from at least one metal used to make a Grignard type reagent and supplying simultaneously an organic non-metallic compound which reacts with the metal to form the Grignard type reagent to surfaces of the chips while they are being formed, whereby the metal and organic compound, subjected to conditions existing during and created by the cutting action including the high localized pressures and temperatures caused by the cutting action, react chemically at the surfaces to form the Grignard type reagent.

3. The method of facilitating a Grignard type of chemical reaction comprising the steps of continually cutting chips from a solid metal body used to make the Grignard organo-metallic halide reagent, supplying simultaneously an organic halide in a suitable liquid solvent to surfaces of the chips while such surfaces are being formed, whereby the metal and organic halide, subjected to conditions existing during and created by the cutting action, react chemically on said surfaces to form the organo-metallic halide, and subjecting said chips as they are freed from the metal body to a body of the solution of the organic halide maintained at a temperature favorable to the continuation of the said reaction initiated on said surfaces during the cutting action but unfavorable to side reactions.

4. The method of facilitating a Grignard type of chemical reaction comprising the steps of continually cutting chips from a magnesium rod, and supplying simultaneously phenyl bromide to surfaces of the chips while such surfaces are being formed, whereby the magnesium and phenyl bromide, subjected to conditions existing during and created by the cutting action, react chemically at said surfaces to form the phenyl magnesium bromide.

5. The method of continuously manufacturing a Grignard reagent comprising the steps of introducing into a chamber a solid metal body used to make the Grignard organo-metallic halide reagent, continually cutting chips from the metal body within the chamber, supplying simultaneously an organic halide in a suitable liquid solvent to surfaces of the chips while such surfaces are

being formed, whereby the metal and organic halide, subjected to conditions existing during and created by the cutting action, react chemically on said surfaces to form the organo-metallic halide, subjecting said chips as they are freed from the metal body to a body of the solution of the organic halide maintained at a temperature favorable to the continuation of the reaction initiated on said surfaces during the cutting action but unfavorable to side reactions, continuously withdrawing from said chamber the solution of Grignard reagent thus formed, and continuously introducing into the chamber fresh organic halide solution at substantially the same rate that the Grignard reagent solution is withdrawn.

6. The method of continuously manufacturing phenyl-magnesium-bromide comprising the steps of maintaining a chamber, continually cutting, in said chamber chips, from a solid body of magnesium, simultaneously supplying to surfaces of the chips as said surfaces are being formed a solution of phenyl-bromide and ether whereby the magnesium and phenyl-bromide subjected to conditions existing during and created by the cutting action react on said surfaces to form the phenyl-magnesium-bromide, subjecting said chips as they are freed from the metal body to a body of the solution in said chamber maintained at a temperature favorable to the continuation of the reaction started on said surfaces during the cutting action but unfavorable to side reactions, continuously withdrawing from said chamber liquid solution containing the phenyl-magnesium-bromide, and continuously introducing into the chamber fresh phenyl-bromide solution at the same rate liquid is withdrawn from the chamber.

7. In the art of facilitating a Barbier type of chemical reaction, the steps of continually cutting chips from at least one metal used to make a Grignard reagent, supplying simultaneously in fluid form an organic halide together with a reacting compound to surfaces of the chips while said surfaces are being formed to cause the metal, organic halide, and compound to react chemically thereon, said compound being the compound necessary to complete the Barbier reaction.

8. The method of manufacturing hexachloroethane comprising the steps of continually cutting chips from a solid body of aluminum within a chamber and supplying simultaneously carbon tetrachloride to surfaces of the chips while such surfaces are being formed whereby the aluminum and carbon tetrachloride, subjected to conditions existing during and created by the cutting action, react at said surfaces, and subjecting said chips to a body of carbon tetrachloride maintained at a temperature favorable to the reaction between the chips and the carbon tetrachloride to produce hexachlorethane.

9. The method of producing a product for reacting with carbon tetrachloride to make hexachlorethane comprising the steps of introducing a solid aluminum body into a chamber, continually cutting chips from the solid aluminum within said chamber and simultaneously supplying carbon tetrachloride to surfaces of the chips while such surfaces are being formed to cause the carbon tetrachloride and the aluminum, subjected to conditions existing during and created by the cutting action, to react readily on the said surfaces, and withdrawing from said chamber the aluminum chips with the reaction products thereon whereby said aluminum chips may be subse-

quently reacted with carbon tetrachloride to form hexachlorethane.

10. In apparatus for carrying out chemical reactions, in combination, a closed reaction chamber, rotating cutting means in said chamber, a passageway connecting the interior of said chamber, with the exterior thereof for permitting the introduction of a solid metallic reactant rod into said chamber, sealing means between said passageway and said metallic rod to exclude atmospheric conditions from the interior of said chamber, feeding means for feeding said metallic rod through said passageway into said chamber at desired rate whereby said cutting means may continually cut small shavings from said metallic rod within said chamber, a passageway for conducting reactant fluid into said chamber and means for controlling the flow of fluid reactant into said chamber, a passageway for conducting reaction products from said chamber, means for controlling the withdrawal of reaction products from said chamber, heat exchange means for maintaining the temperature in said chamber at the desired value, and means for maintaining a controlled atmosphere in said reaction chamber at the desired pressure.

11. In the art of manufacturing chemical compositions, the steps of introducing a reactant metallic solid body into a reaction chamber, continually cutting chips from the body within said chamber, and supplying simultaneously a fluid organic reactant to surfaces of the chips while such surfaces are being formed, to cause the fluid reactant and the solid reactant subjected to the conditions existing during and created by the cutting action to react readily at the said surfaces.

12. In the art of manufacturing chemical compositions, the steps of introducing a reactant metallic solid body into a reaction chamber, continually cutting chips from the body within said chamber, supplying simultaneously a fluid organic reactant to surfaces of the chips while such surfaces are being formed, to cause the fluid reactant and the solid reactant subjected to the conditions existing during and created by the cutting action to react readily at the said surfaces, and regulating the rate of cutting of each chip to favor the reaction.

13. In the art of manufacturing chemical compositions, the steps of supplying an organic fluid reactant to a sealed reaction chamber, continually feeding a reactant metallic solid bar into the chamber containing said reactant fluid, continually cutting chips from the bar within the chamber in the presence of the fluid reactant to cause the metallic solid in the form of chips to react with the fluid reactant in the chamber, and controlling the conditions within the chamber to favor the reaction between the reactants.

14. In the art of manufacturing chemical compositions, the steps of supplying an organic fluid reactant to a sealed reaction chamber, continually feeding a reactant metallic solid bar into

the chamber, continually cutting chips from the bar within the chamber in the presence of the fluid reactant, to cause the metallic solid in the form of chips to react with said fluid reactant in the chamber, and regulating the rate at which the bar is reduced by the cutting action to regulate the overall rate at which the reaction between the metallic solid and the fluid reactant proceeds.

15. In the art of facilitating autocatalytic reactions the steps of introducing a reactant metallic solid body into a chamber, continually cutting chips from the body within said chamber, supplying simultaneously to surfaces of the chips while said surfaces are being formed an organic fluid reactant, the reaction of which with said solid reactant normally has an undesirable induction period, to cause the fluid reactant and the solid reactant subjected to conditions existing during and created by the cutting action, to react readily at the said surfaces without any undesirable induction period to produce on said surfaces a product capable of catalyzing the end reaction between said metallic solid and said organic fluid reactant.
